SAFETY CAR LAMP AND STOVE.

No. 400,071.

Patented Mar. 26, 1889.

UNITED STATES PATENT OFFICE.

OWEN FRANKS AND WILLIAM CARROLL, OF COLUMBUS, OHIO.

SAFETY CAR LAMP AND STOVE.

SPECIFICATION forming part of Letters Patent No. 400,071, dated March 26, 1889.

Application filed December 1, 1887. Serial No. 256,614. (No model.)

To all whom it may concern:

Be it known that we, OWEN FRANKS and WILLIAM CARROLL, both of Columbus, in the county of Franklin and State of Ohio, have 5 invented new and useful Improvements in Safety Car Lamps and Stoves, of which the following is a specification, reference being had to the annexed drawings, forming a part thereof, in which—

10 Figure 1 is a side sectional elevation of a car provided with our improved lamp and stove. Fig. 2 is a detail side elevation of the releasing device. Fig. 3 is a central vertical section of the stove and releasing mechanism. 15 Fig. 4 is a perspective view of the shackle connecting the grate and the ash-pit bottom. Fig. 5 is a plan view of our improved apparatus. Fig. 6 is an enlarged side elevation of the lamp-operating mechanism. Fig. 7 is a 20 vertical central section of a part of a modified form of our improved releasing device, and Fig. 8 shows a modification of the wick-operating device.

Similar letters of reference indicate corresponding parts in all the views.

The object of our invention is to provide simple and efficient devices for extinguishing fires in the car-stoves, and for extinguishing lamps in case of accident.

30 Our invention consists in a stove provided with a hinged grate and a hinged ash-pit bottom, and having below the ash-pit a reservoir containing a fire-extinguishing liquid, and in the combination, with the stove, of a catch-lever adapted to hold the ash-pit bottom and the grate in the position of use, but arranged to be released by the falling of a weight displaced by a sudden movement or stoppage of the car, as in the case of a collision or other 35 accident by which the car is thrown out of its normal position.

It also consists in the combination, with the mechanism, of a device for turning down the wicks of lamps used on the cars, for the purpose of extinguishing the flame.

The stove A is placed in the usual position in the car, and is provided with a combustion-chamber, B, having a grate, C, and an ash-pit, D, having a bottom, E, hinged to the body 50 of the stove. Below the ash-pit D is supported a reservoir, F, which extends through

the floor of the car, and is adapted to hold a fire-extinguishing liquid.

The grate C is connected by a hinge, a, with one side of the stove-body, and is connected with the free end of the ash-pit bottom E by a shackle, G. The shackle G consists of a bar, b, having enlarged heads upon opposite ends, and an arm, c, hinged to the under surface of the free end of the grate, extending through a hole in the upper head of the bar b and provided with a head, d, at its extremity. An arm, c', similar to the arm c, is hinged to the ash-pit bottom E, extending through a hole in the lower head of the bar b and provided with a head, d'. When the ash-pit bottom E is in place, the arm c' engages the upper head of the bar b, and the lower head of the said bar engages the head of the arm c, which supports the grate C; but when the ash-pit bottom E is allowed to fall in the manner presently to be described the bar b slides down upon the arm c, and the arm c slides in the lower head of the bar b and allows both the grate and the ash-pit bottom to drop freely.

H is a crank within the reservoir F, its handle extending to the outer side thereof, as shown in dotted lines, Fig. 3. By operating this handle the crank may be turned against the lower face of the ash-pit bottom E when the same hangs down in the reservoir, in order that said bottom and the grate connected therewith may be raised to their operative positions. The stove is provided with a feeding-door, e, and with an ash-pit door, f, both 80 of which are arranged to be clamped securely in place.

The liquid contained by the reservoir F may consist simply of water or of any of the well-known fire-extinguishing solutions. In 90 a tube, I, inserted in the side of the reservoir F, is contained a rod, J, which is provided with a beveled end, g, which projects under the edge of the ash-pit bottom E when closed, thereby holding the ash-pit bottom and the 95 grate C in the position of use. The rod J passes through a fixed collar, h, in the tube I, and is provided with a collar, i, between which and the fixed collar h is placed a spiral spring, j, which tends to push the rod J forward toward the ash-pit. The end of the tube I is partly closed, and the rod J extends

through the end of the tube and a short distance beyond it. In the side of the tube I is formed a slot, k, through which passes a stud, l, whose upper end is curved over toward the 5 stove A.

Near the stove A is arranged a tubular column, K, which is enlarged in diameter at its upper end to receive the cap L, the said cap consisting of a ring, m, fitted to the top of the 10 column K, and carrying the conical glass portion n of the cap L.

In the tubular column K, near the upper end thereof, is arranged a cross-bar, o, supporting the shallow cup p in the center of the 15 column. In the cup p is placed a spherical weight, M. A screw-threaded rod, N, extends downwardly from the top of the cap L and receives a follower, q, which may be moved up or down upon the rod N by the nut r. 20 Upon the rod N, near the top, is placed a nut, s, between which and the collar t are clamped the spring-arms u, which extend downward opposite the spherical weight M, and are provided at their ends with concave disks v. The 25 follower q is connected by arms w with the springs u at or near their mid-length, and in the cap L is suspended a scale, a'. To the follower q is attached an index, b', which moves in front of the scale a'. The springs 30 u are adjusted by turning the nut r on the rod N. The adjustment of the springs u is such as to allow of a certain amount of motion of the spherical weight M without displacing it from the cup p, while at the same time 35 the springs u have sufficient elasticity to allow the spherical weight M to escape from the cup p when it receives an extraordinary shock.

To the car-floor is attached a support, c², to 40 which is pivoted a lever, O, having a short arm, e', and a long arm, f'. The short arm e' is engaged by the stud l, and the long arm f' extends through a slot, g', in the side of the tubular column K, and is provided with a 45 concave plate, h', for receiving the spherical weight M when the said weight drops. In the side of the tubular column K, near the lower end thereof, is formed an opening, i', which is closed by a screw-cap, j', and through which 50 the spherical weight M is removed from the tubular column K after the operation of the extinguishing mechanism.

Near the outer end of the tube I a standard, P, is secured to the car-floor. In the ears k', projecting from the standard P, is pivoted a 55 detent-lever, Q, whose longer arm extends downward below the pivot to a point opposite the outer end of the rod J. In the standard P is also journalized a trigger, R, having a tooth, l', upon 60 one side and a stud, m', projecting from the opposite side. The tooth l' is engaged by the beveled upper edge of the lever Q. A strap, n', surrounds the standard P and the lever Q, and is provided with an eye, o', by which it 65 may be drawn backward when it is desired to disengage the lever from the tooth l'.

A pipe, S, extends from a point over the

stud m' to the ceiling of the car, thence along the ceiling of the car to a box, T, extending through the center of the car below the lamps 70 U. In the box T are pivoted the levers V, carrying toothed segments p', which are capable of engaging pinions q' on the wick-raising spindles q² of the lamps. All of the lower ends of the levers V are connected by 75 a rod, W, and to one or more of the said levers V is attached a spring, A', which is adapted to move the entire series of levers when the rod W is released. A cord, B', connected with the rod W, passes through the pipe 80 S, and is provided at its extremity with a ring, r', which is received on the stud m', projecting from the trigger R.

In Fig. 7 we have shown a modification of the weight-supporting device, in which the 85 springs u are regulated by a sliding slotted plate, w', in lieu of the follower q and arms w, the springs being received in slots in the plate w'.

The operation of our improved safety car 90 stove and lamp is as follows: The fuel is burned on the grate C in the usual manner, and the ashes and cinders are received upon the hinged bottom E of the ash-pit D. The levers V are placed in position to engage the 95 pinions q'. The weight M rests in the cup p. The ash-pit bottom E is supported by the end of the rod J, and the stud m', projecting from the trigger R, retains the ring r', the trigger itself being prevented from turning by the engagement of the tooth l' with the lever Q. The levers V are in this manner held in position against the pressure of the spring or 100 springs A'. When the car receives a sudden shock, as in a collision, or when it leaves the 105 track or is overturned, the spherical weight 110 M is displaced from the cup p and falls, striking the plate h' on the lever O, causing the lever to tilt, and, by the engagement of the arm e' of the said lever with the stud l, projecting from the rod J, the end of the said rod is withdrawn from beneath the ash-pit bottom E, allowing the ash-pit bottom to drop, and at the same time permitting the grate C to drop, thus discharging the contents of the 115 fire-chamber and the ash-pit into the reservoir F, where the fire is extinguished by the liquid contained by the reservoir. By the same operation the outward movement of the 120 rod J disengages the lever Q from the trigger R, and thus releases the ring r', allowing the spring A' to swing the levers V, and thus revolve the pinions q' and spindles q², turning the lamp-wick down in the lamp, and in this manner extinguishing the flame of the lamp. 125

In Fig. 8 is shown a modification of the lamp-wick-operating device, in which the knurled heads of the wick-operating spindles are operated by a bar provided with notches which allow of the turning of the wick-spindles by 130 hand, in the usual way, the rod being arranged to contact with the knurled heads and turn them when it is moved longitudinally, in the manner described in connection with the rod w.

Having thus fully described our invention, we claim as new and desire to secure by Letters Patent—

5. In a car-stove, the combination, with the stove-body A, provided with tight fire and ash-pit doors, of the hinged grate C, the hinged ash-pit bottom E, the shackle G, connecting the grate and the ash-pit bottom, the reservoir F, containing a fire-extinguishing liquid, and a fastener for holding the ash-pit bottom in the position of use, substantially as described.
10. 2. The combination, with the heater having a connected grate and ash-pit bottom, a lever for raising them into position, a fastener for sustaining them, and a lever for operating the fastener, of a loosely-supported weight above the lever to operate the same by its fall, substantially as set forth.
15. 3. The combination, with a stove, A, provided with the movable grate C, the movable ash-pit bottom E, and the reservoir F, of the tubular column K, the weight-supporting cup p, the spherical weight M, the lever O, arranged to be struck by the falling of the weight M, and the retaining and releasing rod J, substantially as described.
20. 4. The combination, with the tubular column K, weight-supporting cup p therein, and the spherical weight M, of the adjustable springs u, extending at opposite sides of the weight, substantially as described.
25. 5. The combination, with the tubular column K, the weight-supporting cup p, and the spherical weight M, of the cap L, the springs u, the screw-threaded rod N, depending from the inner upper end of the cap, the follower q on the rod, the links w, connecting the springs and follower, the scale a', and the index carried by the follower b', substantially as described.
30. 6. In a safety car stove and lamp, the combination, with a swinging grate and the sliding supporting-rod J, its releasing-lever, and

the weight, of the lever Q, engaging the rod J with its lower end, the trigger R, having a tooth, l', at one side engaging the upper end of lever Q and a stud, m', at its outer side, and connections between the lamps and said stud, substantially as set forth.

50. 7. The combination, with the slotted casing I, and the spring-actuated rod J, projecting at both ends therethrough and having a lug, l, extending up through said slot, of the hollow column K above said casing, a weight, M, loosely supported therein, the pivoted lever O, engaging the lug l with its toe e', and at its other end entering the column K in the path of the weight, the lever Q, engaging at its lower end the outer projecting end of the rod J, and the pivoted trigger R, having a tooth engaging the upper end of the lever Q and having a stud at its opposite end, substantially as set forth.

65. 8. A combined safety-stove and lamp-extinguishing apparatus for cars, comprising the stove having a pivoted grate, a pivoted ash-pit bottom connected with the grate, a reservoir under the ash-pit, a locking-rod entering the reservoir and engaging the ash-pit bottom, the lug l on said rod, the column K, the weight M, supported loosely therein, the lever O, engaging the lug l and extending into the column in the path of the said weight, the lever Q, engaging the outer end of the rod J, the trigger R, engaging the upper end of the lever Q, the wick-operating devices, a rod connecting them, and a connection leading from said rod to the trigger, whereby when the weight falls the trigger, grate, and fire-pot bottom will be released, substantially as set forth.
